HYDRAULIC VALVE

George D. Shaeffer, Detroit, Mich., assignor to
Gar Wood Industries, Inc., Detroit, Mich., a
corporation of Michigan

Application August 8, 1941, Serial No. 406,027

7 Claims. (Cl. 121—40)

The present invention relates to improvements in hydraulic valves and particularly to such valves when used to control the operation of hydraulic elements on road working machines, such as bulldozers and scrapers.

One of the primary objects of the present invention is to provide improvements in valves of the type mentioned in which the possibility of an hydraulic lock in the system is eliminated.

The further object of the present invention is to provide improvements in valves of the type mentioned, including a check and poppet valve in certain of the conduits, in which such check and poppet valve is positively unseated so that there is no possibility of an hydraulic lock in the system.

Other objects of the invention will become apparent from the following specification, the drawings related thereto, and from the claims hereinafter set forth.

Referring to the drawings in which like numerals are used to indicate like parts in the several views throughout:

Figure 1 is a perspective, cross-sectional view of an hydraulic valve with parts in elevation embodying features of the present invention;

Fig. 2 is a cross-sectional view taken substantially along the line 2—2 of Fig. 1;

Fig. 3 is a diagrammatic view illustrating an hydraulic circuit employing the valve of the present invention and illustrating in such circuit a work element in the form of an hydraulic jack; and

Figs. 4, 5, and 6 are diagrammatic, cross-sectional views of the valve of the present invention and showing the elements of such valves in different operative positions, the circular inlet and outlet ports being shown out of their true positions for purposes of clarity.

In certain respects, the present invention relates to the type of valve disclosed in the co-pending application of Louis F. Buran and George D. Shaeffer, Serial No. 354,020, filed August 24, 1940, now Patent No. 2,274,527, issued February 24, 1942.

The valve of the present invention has particular utility when used in association with hydraulic jacks which serve to operate certain elements of road working machines such as scrapers and bulldozers. One of the serious problems in the operation of such machines has been the elimination of the possibility of hydraulic locks in the fluid systems. For example, in bulldozers, hydraulic jacks are utilized to power up and power down the scraper frame and blade. It will be appreciated that, when the frame and blade are powered up, there is considerable force exerted on the jack piston and fluid in the cylinder due to the suspended weight of the frame and blade. The result of this is the transmission of a considerable

back pressure in the hydraulic system, and such back pressure may introduce an hydraulic lock in the system which will prevent proper operation of the device.

Referring first to Fig. 3, the system includes, in general, a valve generally indicated at 10 having an inlet pipe 12 and an outlet pipe 14 connected to an inlet and outlet formed respectively in the valve housing. The inlet conduit 12 connects with the outlet of a conventional pump 16, such pump 16 having an inlet pipe 18 which is adapted to be immersed within the fluid 20, such as oil, contained within a tank 22. The usual means, not shown, for driving the pump is provided.

The valve 10 also has an operating handle 24 attached to a distributing valve plunger for shifting the plunger therein and for controlling the flow of fluid through the valve.

Pipes or conduits 26 and 28 connect with ports formed in the valve 10 and are connected to flexible conduits 30 and 32, respectively. Such conduits 30 and 32 serve to conduct fluid under pressure to and exhaust the fluid from an hydraulic jack generally indicated at 34. Such jack 34 includes the usual cylinder 36 and piston 38 having a piston rod 40 which extends through the cap end thereof. The jack is of the double acting type with the conduit 30 communicating with one end thereof and with the conduit 32 communicating with the cylinder 36 on the opposite side of the piston 38 so that the piston may be powered in either direction. It will be understood that the piston rod 40 is connected to a work element such as the scraper frame of a bulldozer.

Referring to Figs. 1, 2, 4, 5, and 6, the construction of the valve 10 of the present invention is illustrated in detail. Valve 10 comprises a cast metal casing 42 which is formed with a pair of parallel bores 44 and 46 therein. The bore 44 has a plurality of longitudinally spaced annular chambers 48, 50, 52, 54, 56, and 58 communicating therewith. An inlet port 60 is formed through one of the side walls of the casing 42, and an outlet port 62 is formed in the opposite side of the casing and oppositely disposed to the port 60. A pair of branch passageways 64 communicate the inlet port 60 with the annular chambers 50 and 56. A pair of branch passageways 66 communicate the outlet port 62 with the annular chambers 52 and 54.

A passageway 68 communicates the annular chamber 48 with the bore 46, and a passageway 70 communicates the annular passageway 58 with the bore 46, so that the bores 44 and 46 are communicable with each other.

A slideable valve plunger 72 having enlarged cylindrical portions 74, 76, and 78 is slidably disposed within the bore 44 with the ends of the plunger 72 projecting through the open ends of

such bore 44. A link 80 is pivotally connected to one of the projecting ends of the plunger 72 and is operatively connected to the operating handle 24 for sliding the plunger 72 longitudinally of the bore 44. An enlarged annular recess 82 is formed in the housing 42 concentric with the bore 44 and adjacent the link 80. Another annular recess 84 is formed in the opposite side of the housing 42, concentric with the bore 44 and through which the opposite end of the plunger 72 projects.

A cage 86, having longitudinal openings 88 formed therein, is suitably fixed to the side of the casing 42 in concentric relationship to the bore 44. The reduced end 90 of the plunger 72 extends through the case 86 longitudinally thereof. A hub member 92 embraces the end of the reduced portion 90 and has a plurality of radially extending fingers 94 formed integrally therewith. Such fingers 94 extend outwardly to a position adjacent the inner wall of the cage member 86 and are adapted to engage the inturned shoulders 96 on the ends of the cage when such member 92 is in its outermost position. A nut 98 is threaded onto the end of the reduced portion 90 and is adapted to abut against the hub 92.

Another hub member 99 embraces the reduced portion 90 adjacent the bore opening through the casing wall and is formed with a plurality of integral, longitudinally extending legs 101 which are formed with outturned feet 102. Such feet 102 are adapted to be received within the recess 84 and abut against the radial wall thereof.

A helical spring 104 is disposed within the case 86 in surrounding relationship to the reduced end of the plunger 72 and is positioned with one end of the spring abutting against the members 94 and the opposite end of the spring abutting against the feet 102 of members 101.

The hub member 99 abuts against a shoulder 106 formed on the plunger 72 adjacent the reduced portion 90 so that the spring 104 acts against the members 92 and 99 to center the plunger in its normal center position as shown in Fig. 1. The abutment of the hub members 92 and 99 against each other upon movement of the plunger in either direction serves to limit such movement of the plunger 72 in either direction.

The cylindrical portions 74, 76, and 78 are of such lengths with respect to the distances between their corresponding chambers 48, 50, 52, 54, 56, and 58 that when the plunger 72 is in its central or neutral position, as shown in Figs. 1 and 5, the oil under pressure which is introduced through the conduit 12 enters through the inlet port 60 and passes through passageways 64 into the annular passageways 50 and 56 and thence into the bore 44. Such fluid passes then toward the central part of the bore into annular passageways 52 and 54 and thence outwardly through outlet port 62 through branch passageways 66.

When the plunger 72 is shifted to the left, as shown in Fig. 4, the cylindrical portion 74 is so positioned as to block off flow of fluid through the opening of the bore 44. The fluid from the inlet 60 then passes through one of the branch passages 64 into the bore 44 and outwardly through the annular chamber 48 into the passageway 68 which leads to the bore 46. The opposite branch passageway 64 is then blocked off by the cylindrical portion 78. The passageway 70 then communicates with the interior of the bore 44 through the annular passageway 58 and 75

is then discharged outwardly through the annular opening 82 where it may drop back into the tank. With this setting of the plunger, the cylindrical portions 76 and 78 block off the flow of fluid to the outlet port 62.

With the pistons 12 shifted in the opposite direction, that is to the right, as shown in Fig. 6, the high pressure fluid passes into the passageway 70 and from there into the bore 46; and the fluid is exhausted from the bore 46 through the passageway 68. The fluid leaving from passageway 68 passes through the open end of the bore 44 which is surrounded by the case 86 and the leg members 101. Such fluid is free to pass between the legs 101 and to pass through the openings 88 in the cage and fall back into the tank.

From the description of the operation of the structure of the present invention so far described, it will thus be seen that the fluid under pressure may be introduced into either of the passageways 68 or 70 and may be exhausted from either one of such passageways. Also, the fluid may pass directly from the inlet 60 to the outlet port 62 with the plunger set as shown in Figs. 1 and 5.

In order to control the flow of fluid to and from the hydraulic jack 34, novel means are provided within the bore 46. The casing 42 is provided with an outlet passageway 108 which communicates with the bore 46 and which is positioned to the left of the passageway 68, as viewed in Fig. 1. Another annular passageway 110 is formed in the casing between passageways 68 and 70 and communicates with the bore 46. The passageways 108 and 110 communicate with ports 112 and 114, respectively; and such ports 112 and 114 are connected with the conduits 28 and 26, respectively, which lead to the hydraulic jack 34 as shown in Fig. 3.

The passageway 68 communicates with the bore 46 through an annular passageway 116; and the passageway 70 communicates with the bore 46 through an annular passageway 118.

A pair of axially aligned sleeves 120 and 122 are disposed within the bore 44 with the outer ends of such sleeves being fixed in position by means of end cover 124 and an end cap 126. The end cover 124 has an integral, annular portion 128 which projects into the member 120 and which forms a shoulder which abuts against one end of the member 120, with a seal interposed therebetween. The cap 126 has a reduced portion 130 which is telescopically received within the end of member 122 and which forms a shoulder against which the end of member 122 abuts, with a seal interposed therebetween.

The member 120 is formed with an inset, annular portion 132 which is telescopically received within the adjacent end of member 122 and which forms a shoulder against which such end of member 122 abuts. The member 132 also forms an annular shoulder 134 which provides a valve seat.

The member 120 is provided with a plurality of circumferentially spaced openings 136 therearound and with a plurality of another set of circumferentially spaced openings 138 therearound, both sets of which communicate with the annular chamber 108. The member 122 is provided with a set of circumferentially spaced openings 140 therethrough which communicate with the annular chamber 116, another set of circumferentially spaced openings 142 which communicate with the annular chamber 110 and

another set of circumferentially spaced openings 144 therethrough which communicate with the annular chamber 118. The openings 138 are longitudinally positioned close to the valve seat 134 for a purpose that will be pointed out in detail hereinafter.

A valve plunger 146, having longitudinally spaced cylindrical portions 148 and 150, is slidably disposed within the member 122. Such valve plunger 146 is formed with integral, axially extending end projections 152 and 154.

A helical spring 156 is positioned so that one end is received within a recess 158 formed in the cap 126 with its opposite end embracing the projection 154 so that the valve plunger 146 is resiliently urged to the left, viewing Fig. 1.

A cup-shaped, check and poppet valve 160 is slidably received within the member 120 with the face of such element 160 extending toward the valve plunger 146. Such face is formed with a taper 162 which is adapted to seat against the annular valve seat 134.

A helical spring 164 is so disposed that one end thereof is received within the recess of projection 128, and the opposite end thereof is received within the recess of the cup-shaped member 160 so that such valve element 160 is urged toward the right, viewing Fig. 1. The spring 164 thus acts to seat the tapered portion 162 on the valve seat 134 and therefore stronger than the spring 156.

The valve element 160 is of such a length that when it is in the position shown in Fig. 1, fluid within passageway 108 may communicate with the interior or recess of the member 160 through the openings 138. At this time, the openings 138 are shut off.

Referring to Fig. 4, when the plunger 72 is so set that the fluid under pressure enters into passageway 68, such fluid passes through the openings 140 and unseats the valve element 160 so that such fluid may then pass through openings 138 into the annular passageway 118 and out through port 112 into the conduit 28. Thus, the plunger 38 is moved upwardly. With such plunger operatively connected with a work element such as the frame and blade of a bulldozer so that movement in that direction raises the bulldozer, it will then be seen that when the plunger 72 is returned to its neutral position, the weight of the frame and blade will exert a back pressure in conduit 28 which will be exerted on the inside of the valve element 160 through openings 138. This is the "hold" position and the blade and frame will be held in such elevated position until the plunger 72 is shifted again.

With the plunger 72 set in the position shown in Fig. 4, it will be seen that the fluid on the opposite side of the plunger 38 will be exhausted through conduits 30, 28, through port 114, into annular passageway 110, through openings 142 and 144 into annular passageway 118 and thence into passageway 70 from which it is discharged through the opening 82. The pressure of the fluid from passageway 68 within the member 122 will have shifted the valve plunger 146 to the right as shown in Fig. 4.

With the elements in the position shown in Fig. 5, which is the neutral or hold position, the back pressure due to the weight of the frame and blade, as mentioned above, will exert a force on the valve element 160 which forces it toward its seat 134. When the plunger 72 is moved to the position shown in Fig. 6 so that the fluid under pressure enters through conduit 70 in order to power the piston 38 in the opposite direc-

tion, the following action takes place which will prevent any hydraulic lock in the system due to the above mentioned back pressure. It will be appreciated that in order to prevent such hydraulic locking, the valve element 160 must be unseated so that the fluid on the underside of the piston 38 may be exhausted through the openings 138 and pass into the passageway 68 which is then serving as an exhaust passageway.

This is accomplished in that the end 152 of the valve plunger 146 is engageable with the face of the member 160 and when the fluid under pressure enters through openings 144, such fluid cannot pass into the passageway 110, due to the position of the cylindrical portion 150, until such valve plunger 146 has moved a predetermined distance to the left. In moving such distance, the projection 152 strikes against the member 160 and the high pressure from the passageway 70 acting upon the valve piston 146 will thereby cause the valve element 160 to be unseated and positively move such element 160 to the left providing exhaust communication between the openings 138 and the interior of the projection 132. The fluid within the chamber 108, including that behind the element 160, may then be exhausted through the passageway 140 into the passageway 68 from which it may pass through the open end of the bore 44, as shown in Fig. 6.

The valve plunger 146 may then continue in its movement to the left to the full position shown in Fig. 6 so that the fluid under pressure may enter the annular passageway 110 through the openings 144 and 142. From the passageway 110, the fluid under pressure passes through port 114 and into the upper end of the cylinder 36 through the conduits 26 and 30.

It is pointed out that the relative longitudinal distances between the openings 142 and 144 and between the valve seat 134 and openings 138 is such that the fluid under pressure from the passageway 70 cannot pass through openings 142 into the passageway 110 until the element 160 has been moved to open the openings 138 for the exhaust of fluid therethrough.

In describing another operation of the valve, when the device is powered down as shown in Fig. 6, and when after such powering down the valve is returned to its hold position, as shown in Fig. 5, there may be a back pressure in the conduit 114. Such back pressure is the result of powering down to such an extent that the forward end of the tractor is raised off the ground. With the valve of the present invention an hydraulic lock cannot result.

From the drawings it will be seen that after such a hold position, if it is desired to power up, as illustrated in Fig. 4, the fluid under pressure enters the bore 46 through passageway 68. Such passageway communicates with the interior of the bore between the valve piston portion 148 and the valve element 160 so that its pressure is effective on the faces of the valve 148 and that portion of the face of valve element 160 which is within the reduced annular portion of the offset 132. The effective area of the valve 162 is of less area than the effective area on valve portion 148. Since the valve 146 is balanced when in the hold position due to the pressure from passageway 110 acting upon the inside faces of portions 148 and 150, it will be seen that the pressure from passageway 68 acting on the outside face of valve portion 148 will cause it to move from the position shown in Fig. 5 to the position shown in Fig. 4 to thereby communicate the port 114 with the passageway 70. This

movement of the valve 142 will take place before the valve 160 is unseated. There, therefore, cannot be any hydraulic lock.

From the above it will be seen that there can be no hydraulic locking of the valve of the present invention in moving from the hold position to either of the other positions, or in any other position of the valve.

What is claimed is:

1. In a hydraulic system, a cylinder and piston work means, hydraulic valve means for distributing fluid under pressure through first and second conduits to said cylinder on opposite sides of said piston, said valve means including a casing having a chamber therein, valve means for controlling the inlet and exhaust of fluid from said chamber through first and second passageways, said first and second passageways being arranged for the passage of fluid into and out of said chamber at spaced points therealong, first and second ports communicating with said chamber and communicating with said first and second conduits, respectively, a valve piston slidably disposed within said chamber and operable to control the flow of fluid to and from said first 25 passageway and to and from said first port, a valve element slidably disposed within said chamber and operable to control the flow of fluid to and from said second passageway and to and from said second port, said valve piston and said 30 valve element being separable and engageable and being movable toward and away from each other, said second passageway communicating with said chamber between said valve piston and said valve element so that fluid under pressure from said second passageway is effective on both said valve element and said valve piston, said first passageway communicating with said chamber in such a position that fluid under pressure therefrom is effective on said valve piston, said 40 valve piston and said valve element being so disposed with respect to each other and with respect to said ports that when fluid under pressure is introduced into said chamber through said first passageway said valve piston unseats said valve element before fluid under pressure can flow from said first passageway to said first port.

2. In a hydraulic system, a cylinder and piston work means, hydraulic valve means for distributing fluid under pressure through first and second conduits to said cylinder on opposite sides of said piston, said valve means including a casing having a chamber therein, valve means for controlling the inlet and exhaust of fluid from said chamber through first and second passageways, said first and second passageways being arranged for the passage of fluid into and out of said chamber at spaced points therealong, first and second ports communicating with said chamber and communicating with said first and second conduits, respectively, a valve piston slidably disposed within said chamber and operable to control the flow of fluid to and from said first passageway and to and from said first port, a valve element slidably disposed within said chamber and operable to control the flow of fluid to and from said second passageway and to and from said second port, said valve piston and said valve element being separable and engageable and being movable toward and away from each other, said second passageway communicating with said chamber between said valve piston and said valve element so that fluid under pressure from said second passageway is effective on both said valve element and said valve piston, said

first passageway communicating with said chamber in such a position that fluid under pressure therefrom is effective on said valve piston, said valve piston and said valve element being so disposed with respect to each other and with respect to said ports that when fluid under pressure is introduced into said chamber through said first passageway said valve piston is in direct engagement with said valve element and moves to unseat said valve element before fluid under pressure can flow from said first passageway to said first port.

3. In a hydraulic system, a cylinder and piston work means, hydraulic valve means for distributing fluid under pressure through first and second conduits to said cylinder on opposite sides of said piston, said valve means including a casing having a chamber therein, valve means for controlling the inlet and exhaust of fluid from said chamber through first and second passageways, said first and second passageways being arranged for the passage of fluid into and out of said chamber at spaced points therealong, first and second ports communicating with said chamber and communicating with said first and second conduits, respectively, a valve piston slidably disposed within said chamber and operable to control the flow of fluid to and from said first passageway and to and from said first port, a check valve element slidably disposed within said chamber and operable to control the flow of fluid to and from said second passageway and to and from said second port, said valve piston and said valve element being separable and engageable and being movable toward and away from each other, said second passageway communicating with said chamber between said valve piston and said valve element so that fluid under pressure from said second passageway is effective on both said valve element and said valve piston, said first passageway communicating with said chamber in such a position that fluid under pressure therefrom is effective on said valve piston, said valve piston and said valve element being so disposed with respect to each other and with respect to said ports that when fluid under pressure is introduced into said chamber through said first passageway said valve piston is in direct engagement with said valve element and moves to unseat said valve element before uncovering said first port so that fluid under pressure can flow from said first passageway to said first port.

4. In a hydraulic system, a cylinder and piston work means, hydraulic valve means for distributing fluid under pressure through first and second conduits to said cylinder on opposite sides of said piston, said valve means including a casing having a chamber therein, valve means for controlling the inlet and exhaust of fluid from said chamber through first and second passageways, said first and second passageways being arranged for the passage of fluid into and out of said chamber at spaced points therealong, first and second ports communicating with said chamber and communicating with said first and second conduits, respectively, a valve piston slidably disposed within said chamber and operable to control the flow of fluid to and from said first passageway and to and from said first port, a valve element slidably disposed within said chamber and operable to control the flow of fluid to and from said second passageway and to and from said second port, said valve piston and said valve element being separable and engageable

and being movable toward and away from each other, said second passageway communicating with said chamber between said valve piston and said valve element so that fluid under pressure from said second passageway is effective on both said valve element and said valve piston, said first passageway communicating with said chamber in such a position that fluid under pressure therefrom is effective on said valve piston, said valve piston being movable away from said valve element at a lower unit fluid pressure than said valve element, said valve piston and said valve element being so disposed with respect to each other and with respect to said ports that when fluid under pressure is introduced into said chamber through said second passageway said valve piston is moved to permit flow of fluid from said first port to said first passageway before said valve element is unseated to permit flow of fluid to said second port.

5. In a hydraulic system, a cylinder and piston work means, hydraulic valve means for distributing fluid under pressure through first and second conduits to said cylinder on opposite sides of said piston, said valve means including a casing having a chamber therein, valve means for controlling the inlet and exhaust of fluid from said chamber through first and second passageways, said first and second passageways being arranged for the passage of fluid into and out of said chamber at spaced points therealong, first and second ports communicating with said chamber and communicating with said first and second conduits, respectively, a valve piston slidably disposed within said chamber and operable to control the flow of fluid to and from said first passageway and to and from said first port, a valve element slidably disposed within said chamber and operable to control the flow of fluid to and from said second passageway and to and from said second port, said valve piston and said valve element being separable and engageable and being movable toward and away from each other, said second passageway communicating with said chamber between said valve piston and said valve element so that fluid under pressure from said second passageway is effective on both said valve element and said valve piston, said first passageway communicating with said chamber in such a position that fluid under pressure therefrom is effective on said valve piston, said valve element being of less effective area when seated than said valve piston, said valve piston and said valve element being so disposed with respect to each other and with respect to said ports that when fluid under pressure is introduced into said chamber through said second passageway said valve piston is moved to permit flow of fluid from said first port to said first passageway before said valve element is unseated to permit flow of fluid to said second port.

6. In a hydraulic system, a cylinder and piston work means, hydraulic valve means for distributing fluid under pressure through first and second conduits to said cylinder on opposite sides of said piston, said valve means including a casing having a chamber therein, valve means for controlling the inlet and exhaust of fluid from said chamber through first and second passageways, said first and second passageways being arranged for the passage of fluid into and out of said chamber at spaced points therealong, first and second ports communicating with said chamber and communicating with said first and second conduits, respectively, a valve piston slidably dis-

posed within said chamber and operable to control the flow of fluid to and from said first passageway and to and from said first port, a valve element slidably disposed within said chamber and operable to control the flow of fluid to and from said second passageway and to and from said second port, said valve piston and said valve element being separable and engageable and being movable toward and away from each other, said second passageway communicating with said chamber between said valve piston and said valve element so that fluid under pressure from said second passageway is effective on both said valve element and said valve piston, said first passageway communicating with said chamber in such a position that fluid under pressure therefrom is effective on said valve piston, unbalanced springs urging said valve piston and said valve element toward each other, said valve piston and said valve element being so disposed with respect to each other and with respect to said ports and said springs being unbalanced so that when fluid under pressure is introduced into said chamber through said second passageway said valve piston is moved to permit flow of fluid from said first port to said first passageway before said valve element is unseated to permit flow of fluid to said second port.

7. In a hydraulic system, a cylinder and piston work means, hydraulic valve means for distributing fluid under pressure through first and second conduits to said cylinder on opposite sides of said piston, said valve means including a casing having a chamber therein, valve means for controlling the inlet and exhaust of fluid from said chamber through first and second passageways, said first and second passageways being arranged for the passage of fluid into and out of said chamber at spaced points therealong, first and second ports communicating with said chamber and communicating with said first and second conduits, respectively, a valve piston slidably disposed within said chamber and operable to control the flow of fluid to and from said first passageway and to and from said first port, a valve element slidably disposed within said chamber and operable to control the flow of fluid to and from said second passageway and to and from said second port, said valve piston and said valve element being separable and engageable and being movable toward and away from each other, said second passageway communicating with said chamber between said valve piston and said valve element so that fluid under pressure from said second passageway is effective on both said valve element and said valve piston, said first passageway communicating with said chamber in such a position that fluid under pressure therefrom is effective on said valve piston, said valve piston being movable away from said valve element at a lower unit fluid pressure than said valve element, said valve piston and said valve element being so disposed with respect to each other and with respect to said ports that when fluid under pressure is introduced into said chamber through said first passageway said valve piston unseats said valve element before fluid under pressure can flow from said first passageway to said first port and that when fluid under pressure is introduced into said chamber through said second passageway said valve piston is moved to permit flow of fluid from said first port to said first passageway before said valve element is unseated to permit flow of fluid to said second port.

GEORGE D. SHAEFFER.
